ABSTRACT OF THE DISCLOSURE

The present invention relates to an improvement in cooling heated workpieces and, more particularly, to a device for the controlled cooling of elongated workpieces, such as hot rods and bars immediately after they issue from a rolling mill.

The desirability of providing a procedure and apparatus for control cooling heated rods or bars issuing from a rolling mill, either prior to the cooling thereof or immediately thereafter, has been well recognized in the art. The heated workpieces may possess a temperature of 1,900° F. as they issue from the rolling mill. In this regard in order to obtain superior metallurgical characteristics and optimum surface scale condition, it is desired to rapidly cool in a controlled manner the workpieces to a temperature of approximately 1,300° F. The realization of such an objective becomes extremely difficult in dealing with very high speed, extremely high tonnage mills, for example, in providing for such coolant for a rod mill wherein the issuing speed of the rod may exceed 7,200 feet per minute and wherein the mill may roll three strands simultaneously. To date there has not been developed an economic and efficient method and device for meeting the cooling requirements.

The present invention provides an apparatus designed to successfully handle rapidly produced bundles of rods, bars or the like from a high-speed, high-production rolling mill and control cool the bundles in a manner that will both satisfy the high output rate of the mill and assure the required cooling.

In one of its aspects the present invention provides a continuous conveyor, intermittently driven, arranged to cooperate with the laying or pouring reels of a rod or bar mill, onto which conveyor the formed bundles are transferred, and wherein during advancement by the conveyor the bundles are enclosed and subject to continuous cooling medium until discharged from the conveyor, the construction being such that each heated bundle can be cooled as long as necessary without interfering with the production of the mill and at the same time the conveyor is always free to receive new bundles from the reels.

More particularly, there is provided in sequence a rod coiling station, a rod bundle cooling station, and a rod bundle discharge station, said rod coiling station including means for forming bundles of rods and the like issuing from a rolling mill, means for moving the bundles once they have been formed to a first position, means for

2

transferring the formed bundles from the first position to said rod bundle cooling station, including a conveyor arranged to one side of the bundle forming means, said conveyor constituting a continuous conveyor made up of a number of individual cars each including a coil receiving platform, each coil receiving platform also adapted to support a cover for a bundle, means for engaging said covers at a position in front of the bundle forming means to position the covers over the bundle forming means so that a coil removed from the bundle forming means can be positioned in said cover, said bundle and cover being transferrable to the conveyor, means for intermittently advancing said conveyor so as to position one of its cars in a position to receive bundles formed by said bundle forming means, openings in said platforms communicating with first passageways, formed in said cars, a central cooling medium passageway encircled by said conveyor, said central passageway having a plurality of second passageways communicating with each of said 15 first passageways of said cars, means for delivering force cooling fluid into said central passageway to cool the bundle while supported by said cars, said discharge station arranged adjacent a portion of said conveyor of cooling station, means for engaging said cover when in said discharge station to remove said cover and its supporting bundle onto a discharge conveyor, means for removing said cover from said bundle, so that the bundle may be advanced away from said conveyor when in said discharge station, said discharge conveyor adapted to receive bundles from said conveyor of said cooling station after which said cover can be again placed on its associated car and conveyed to said coiling station.

These objects and advantages, as well as others, will be more evident from the following description of one embodiment of the present invention, when read along with the accompanying drawings of which:

FIGURE 1 is a plan view of rod coiling, cooling, and discharge stations incorporating the features of the present invention,

FIGURE 2 is a sectional view taken on lines II—II of FIGURE 1,

FIGURE 3 is a sectional view taken on lines III—III of FIGURE 1, and

FIGURE 4 is a sectional view taken on lines IV—IV of FIGURE 1.

With reference to the drawings, and particularly to FIGURE 1, the illustrated equipment, for convenience of description, is divided into three areas. The first area is defined as the bundle coiling station, the second the bundle cooling station, and the third the bundle discharge station, the drawing being accordingly marked for easy identification.

With reference to the coiling station there is provided two rod coiling apparatus 10 and 11 which conform to well-known construction, and for which reason a detailed description thereof is not deemed necessary. A typical example of such coilers is shown in U.S. Patent 2,595,006 which issued to J. W. Sheperdson on Apr. 29, 1952. FIGURE 2 shows the bottom platform 12 of one of the coilers which is connected to a central actuating rod 13, upward displacement of which rod raises a rod bundle from within the coiler to an upper elevation, which position is illustrated in FIGURE 2. On one side of the coil-

ing station there is arranged a continuous-type conveyor 14, intermittently driven, which makes up an essential part of the cooling station.

As FIGURE 2 indicates, the conveyor 14 is comprised of a number of individual cars 15 which, as shown in FIGURE 3, each comprise two pair of wheels 16 and 17 which are received on parallel tracks 18, the cars being pivotally connected together by links 19, shown in FIGURE 1. The upper portions of the cars 15 are provided with horizontal platforms 21 which it will be noted are in the same elevation as the extreme upper position of the platform 12 of the rod coilers 10 and 11.

In still referring to FIGURE 2, it will be noted that the platforms 21 of the cars are made of such a width as to receive rod bundles shown in outline form and identified with the capital letter B and outward thereof to receive and support covers 22. It will be appreciated that each car is provided with one of these covers, the covers being tubular in form and are provided with annular lips 23 and 24, having channel portions, the purpose for which will be explained later. The covers 22 are portable to the extent that they are readily transportable from the cars 15 to a position over the coilers 10 and 11, in which position they are adapted to be carried by a platform 28 which is provided with openings sufficient to allow the platform 12 of the coiler, together with rod bundles, to pass. Two covers 22 are advanced from two of the cars 15 when the cars are positioned in front of the coiling station to a position over the rod coilers by individual rams 31 and 32, the rams comprising horizontally extended beams 33 which are slidably supported in uprights 34, the lower surface of the rams, although not shown, being provided with racks which engage pinions, also not shown, the pinions being driven by shafts 35 to which are connected individual gear reduction motor sets 36. As best shown in FIGURE 1, the rams 31 and 32 have at their end adjacent the coilers 10 and 11 bundle pushing elements 38 which are of sufficient size to engage the covers 22 to push the covers from the coiling station to the cooling station, and more particularly, from the platforms 12 over the platform 28 onto the platforms 21 of the cars 15. The rams 31 and 32 also are provided with pivotal hooks 39 to each of which there is connected piston cylinder assemblies 41, the hooks being so arranged relative to the lower channels 24 of the covers 22 so as to enter into the channels and on the retraction of the rams 31 and 32, the covers will be moved from the cars onto the platform 28.

Turning to the cars 15, as shown in FIGURE 1, towards the bottom of the drawing there is indicated in a broken-away section a plan of one of the platforms 21 in which it will be observed that there is provided a grated opening 42, the opening communicating with a passageway 43 formed below the platforms 21 which extend towards the center of the conveyor 14, the conveyor being formed with a central opening which actually forms a central conduit 44 which runs approximately the full length of the conveyor and has a series of opposed openings 45 and 46 which are in the same elevation and communicate with the passageway 43 of the car 15. The opening or conduit 44 is adapted to receive a controlled amount of fluid, such as air, water or atomized air from a fan 47 which is driven by an electrical motor 48.

As noted previously, the conveyor 14 is driven intermittently so as to register a car in front of each of the two coilers 10 and 11 for which purpose there is provided a motor-gear drive 49 shown also only in FIGURE 1.

Turning now to the covers 22 and, particularly FIGURE 2, it will be noted that each cover is provided with a fluid deflecting plate 51 which is slidably mounted on a central shaft 52 adapted to move substantially the full distance of the shaft from a place at the bottom of

the cover, which is shown in phantom in FIGURE 2, to the top thereof, as shown in full lines in the same figure. The plate 51 is urged towards the bottom by either a counterweight or a spring so that as the bundle is raised out of the coiler, its upper surface engages the plate 51 and the plate will come to rest on top of the bundle. The purpose of the plate 51 is to prevent the fluid issuing from the bottom of the car from passing directly up through the center of a coil, but instead causes the fluid to pass radially through the coil after which it passes up through an opening 53 provided in the top of the cover 22.

Turning now to the coil discharge station and to FIGURES 1 and 4, it will be first noted that there is provided a second intermittently driven conveyor 56, the purpose of which is to take away the cooled bundles from the cooling station. The bundles and covers, once positioned adjacent the conveyor 56, as shown in FIGURE 1, are adapted to be readily removed from the conveyor 14 and transferred to the conveyor 56 by a reciprocating ram 57, arranged essentially in the same elevation as the platforms 21 of the cars 15 and the conveyor 56.

The ram 57, as the rams 31 and 32, are provided with cover pusher elements 58 and a hook 59 identical in construction and function to the similar components of the pusher rams 31 and 32. The hook 59 thus is adapted to engage the lower channel 24 of the cover and remove the channel together with the encircled bundle from the platform 21 of one of the cars 15 to the conveyor 56. Once on the conveyor 56, as shown in FIGURE 4, the cover is adapted to be lifted vertically off of the bundle so as to free the bundle to be moved away by the conveyor 56. The cover 22 is raised from the bundle by means of a vertical displaceable arm 61 which is connected to a vertical shaft 62, the shaft being vertically received in a standard 63, the lower end of the shaft being connected to a piston cylinder assembly 64 which raises the arm 61, the arm being provided with projections 65 which engage the channels of the cover 22 through which means the cover is raised off the bundle.

Before briefly describing the operation of the disclosed embodiment of the present invention, it should be emphasized that the length of the conveyor 14 is to a great extent a function of the required cooling time necessary to cool the bundles from the time they are transferred from the coilers 10 and 11 until the time they are discharged onto the discharged conveyor 56. Its length is also a function of the production capacity of the rod mill. Thus, it will be appreciated that should more cooling time be required, or a greater bundle capacity be found necessary, these conditions can be simply met by varying the length of the conveyor 14 to suit the particular condition.

Turning now to a brief description of the operation of the various components above described, it will be assumed that a bundle B has been formed in the coiler 11 and that the platform 12 of the coiler has been raised to position the bundle in line with the platform 28, the conveyor 14 being synchronized relative to the elevation of the bundle so as to position a car 15 in front of the coiler 11, thereby allowing on operation of the ram 33 a cover 22 to be positioned above the coiler prior to the bundle being raised out of the coiler. Once this occurs the ram 32 will be operated to transfer the cover 22 together with the bundle to the waiting car 15. Once the bundle is so transferred, and immediately upon being received by the platform 21 of the car, the coil will be subject to the cooling, as previously noted. It should be noted here that the cover plate 51 will engage the top of the bundle as soon as it has been raised into the cover and when the coil was transferred to the car, the plate will cause the fluid to pass radially out through the bundle and prevent it from passing up through the center thereof. Once the cover is placed back on the car 15, the conveyor can be operated to bring into position a subsequent car for

receiving the next bundle. The bundle just described as being transferred from the coiler 11 then will be successively moved around the conveyor 14 during which time it will be continuously cooled at a controlled rate sufficient to reduce its temperature to the required low level to obtain the desired metallurgical characteristics. This will bring the bundle B to the discharge station, and the conveyor will be automatically stopped to register the car 15 in front of the conveyor 56 and allow the ram 57 to engage the cover 22 and transfer the cover and bundle onto the conveyor 56. At this time the cover will be raised by operation of the piston cylinder 64 which will cause the arm 61 to engage the cover and lift it off the bundle so that the conveyor 56 can be operated to convey the bundle away. Once this occurs, the cover is again lowered down onto the conveyor 56, and the ram 57 again operated to push the cover back onto the car 15 and the car can be advanced to the cooling station.

It will be appreciated that various other forms of the present invention can be utilized without departing from its scope and that the invention can be employed to cool other products other than hot rods and bars.

In accordance with the provisions of the patent statutes, I have explained the principle and operation of my invention and have illustrated and described what I consider to represent the best embodiment thereof. However, I desire to have it understood that within the scope of the appended claims, the invention may be practiced otherwise than as specifically illustrated and described.

I claim:

1. In an arrangement for processing metallic workpieces comprising in operative sequence:
a heated workpiece coil forming station,
a coil cooling station, and
a coil discharge station,
said workpiece coil forming station including a pair of separate means for forming coils from heated workpieces issuing to said separate means,
a plurality of covers constructed to be placed over the coils formed by said coil forming means,
means for transferring a coil and a cover from said coil forming station to said coil cooling station,
said coil cooling station including a continuous closed loop conveyor arranged on a common side of the pair of coil forming means, and having means for supporting a plurality of coils together with their covers and wherein the supporting means passes in an orbital path while supporting coils,
means for intermittently advancing said conveyor so as to present a portion of the conveyor in position to receive a coil from said coil forming station,
means for supplying a heat treating medium to said coils while supported by said conveyor,
said coil discharge station being arranged to have a portion thereof adjacent to said coil cooling conveyor, means for transferring a coil from said conveyor to said discharge station, and wherein the length of said conveyor is such that a coil transferred to it is subject to the necessary heat treatment before it is advanced to the discharge station.

2. In an arrangement for processing metallic workpieces according to claim 1, wherein said conveyor includes means for supporting said covers, and wherein the arrangement includes:

means for manipulating a cover over a coil immediately after it has been formed, and
means for transferring a coil and cover as a unit to said conveyor.

3. In an arrangement for processing metallic workpieces according to claim 1, wherein said conveyor includes a number of cars, each adapted to support a single coil, and each having a coil receiving and supporting platform, said platforms being constructed and arranged to receive

said coil from said coil forming station and to support a cover when enclosing a coil.

4. In an arrangement for processing metallic workpieces according to claim 3, wherein said conveyor is arranged to present at least 2 cars in front of said coil forming station and wherein the arrangement includes a separate reciprocatory means for each coil forming means arranged on the side of the coil forming means opposite said conveyor and having a member for connecting itself to a cover while supported by said conveyor and moving a cover to a superposed position relative to the coil forming means.

5. In an arrangement for processing metallic workpieces according to claim 3, wherein the length of the conveyor and the number of cars it comprises is a function of the number of coil forming means, and the time required to heat treat a coil from the time it is received by said conveyor to the time it is conveyed to said discharge station.

6. In an arrangement for processing metallic workpieces according to claim 3, in which each said platform has an opening communicating with a first passageway formed in each car:

a primary cooling medium passageway encircled by said conveyor, said primary passageway having a plurality of auxiliary passageways communicating with each of said first passageways of said cars, and means for delivering the cooling medium to said primary passageways for continuously cooling said coils when supported by said cars.

7. In an arrangement for processing metallic workpieces according to claim 1, wherein said coil forming means is arranged at a position below said conveyor and each include means for raising a coil after it has been formed to the elevation of said conveyor from where it is transferred to said coil cooling station.

8. In an arrangement for processing metallic workpieces according to claim 1, wherein each cover includes a cooling medium deflector plate,

means for allowing said plates to be displaced by a coil when a coil is positioned within a cover, and wherein the plates prevent the cooling medium from escaping from one end of a coil enclosed by said cover.

9. In an arrangement for processing metallic workpieces comprising in operative sequence:

a heated workpiece coil forming station,
a coil cooling station, and
a coil discharge station,
said workpiece coil forming station including a pair of separate means for forming coils from heated workpieces issuing to said separate means,
means for transferring coils formed in said coil forming station to said coil cooling station,
said coil cooling station including a continuous closed loop conveyor arranged on a common side of the pair of coil forming means, and having means for supporting a plurality of coils and wherein the supporting means passes in an orbital path while supporting coils,

means for intermittently advancing said conveyor so as to present a portion of the conveyor in position to receive a coil from said coil forming station,
means for supplying a heat treating medium to said coils while supported by said conveyor,
said coil discharge station being arranged to have a portion thereof adjacent to said coil cooling conveyor,

means for transferring a coil from said conveyor to said discharge station, and wherein the length of said conveyor is such that a coil transferred to it is subject to the necessary heat treatment before it is advanced to the discharge station,

said discharge station includes a discharge conveyor having a portion thereof arranged adjacent said coil cooling conveyor,
means at said discharge station for connecting itself to a cover when brought to said discharge station and

adapted to transfer said cover and enclosed coil as a unit onto said discharge conveyor,
 means for removing said cover from a coil so that the coil can be advanced away from said cooling conveyor by said discharge conveyor,
 means for intermittently advancing said discharge conveyor to effect movement of a coil supported thereby, and
 means for engaging the removed cover to effect a transferring of said cover to an empty car of said coil 10 cooling conveyor for retransfer to said coil forming station.
